ERASER

Carl C. Harris, Orange, Mass.

Application May 8, 1934, Serial No. 724,529

3 Claims. (Cl. 120—38)

This invention relates to an eraser for use on thin pencils or to a thin eraser adapted for uses similar to those of thin pencils.

The principal objects of the invention are to provide a propelled eraser in a thin casing which can be placed between the leaves of a book or carried flat in a pocket; to provide means whereby, as the eraser wears down, it can be projected outwardly and can be adjusted backwardly so as to provide for its efficient manipulation as an eraser; to provide a casing which will be capable of use with a propelled lead in the other end; to provide magazines for one or more leads at the side of the eraser propelling means; to provide a similar casing in such form that it will carry the eraser without its combination with a pencil holding means, and to provide simple means for preventing the propelling screw from rotating and simple means for connecting the propelling screw in rotational relation to the eraser.

Other objects and advantages of the invention will appear hereinafter.

Reference is to be had to the accompanying drawing, in which

Fig. 1 is a plan of a combined pencil and eraser constructed in accordance with this invention;

Fig. 2 is an edge view of the same;

Fig. 3 is a view similar to the eraser part of Fig. 1 on enlarged scale;

Fig. 4 is a similar view of the eraser itself and propelling screw removed from the casing;

Figs. 5, 6 and 7 are transverse sectional views respectively on the lines 5—5, 6—6 and 7—7 of Fig. 3;

Fig. 8 is a perspective view of the end of the eraser and the clip which holds it, and

Fig. 9 is a view similar to Fig. 3 of a modified form of the invention in which the pencil part is eliminated and the article serves only as an eraser.

An eraser for pencil or ink, formed of a thin piece of erasing material with a guard to hold it in position, has several advantages. In the first place the erasing can be controlled to apply to a single line or letter, thereby saving in the rubber as in an ordinary eraser much surface is rubbed without accomplishing anything.

This invention relates to such an eraser and a holder therefor used separately or in connection with a thin or flat pencil. Such an eraser is particularly desirable with a thin pencil and, in fact, is almost indispensable. On account of the thinness of the eraser it is desirable to provide it with a guard and with means for propelling and re-

Referring to the drawing, a long metallic pencil case 10 is provided having a lead 11 at one end adapted to be propelled by means of a nut 12 and screw 9 and provided with two side cylindrical magazines 13 for extra leads. In the center is 5 a cylindrical compartment 14 for the lead 11, screw 9, and the screw 18 for the eraser.

In this case the part 15 of the main casing at one end receives the flat thin eraser 16 and its associated parts. This also involves a nut 17 for 10 operating the eraser 16. Usually less than half the length of the pencil case is taken up with the eraser magazine, the lower part being taken up with the mechanism for propelling the lead.

The magazines 13 for the extra leads are open 15 at the eraser end and are filled and emptied from that end being covered by a member for holding the eraser, as will appear hereinafter.

The arrangement for operating the lead does not in itself constitute a part of this invention and 20 is shown and described in my Patent No. 1,975,788, granted Oct. 9, 1934, on an application filed April 13, 1933, Serial No. 665,913.

The central cylindrical compartment 14 not only provides space for the lead 11 and the propelling means therefor but also for the screw 18 cooperating with a nut 17. This nut is located in an opening 19 through the casing of the same cross sectional area as the nut so that the nut can be rotated and cannot move longitudinally 30 and the screw will be propelled in one way or the other according to the direction of rotation of the nut. The screw 18 is provided with a flattened end 20 operating in a groove 20^a of a corresponding shape and its opposite end is provided with a 35 head 21 separated from screw threads by a neck 22.

The eraser 16 is provided with a sheet metal clip 23 doubled over it and having prongs 24 pressed inwardly to hold the rubber eraser 16 40 in the clip. The clip also has a T-shaped slot 25 to receive the head 21 and neck 22 so that the screw 18 can be attached readily to the clip and thereafter will move it with the screw. The thin eraser 16, of course, projects through the 45 metallic casing 15 which serves as a shield to prevent the bending of the rubber except that part which is projected through the end of the casing. This enables the user to make his eraser as stiff or as limber as he may see fit and this by a 50 very simple adjustment of the nut 17 so that no one is likely to use an eraser which is in improper condition for use on account of projecting too far or not far enough. This makes it possible to erase a single line or letter very readily without 55

wearing off a large area of the eraser to no purpose.

In the first eight figures the invention is shown as applied to a pencil of a flat type, such as shown in my above mentioned application, where it is particularly useful and almost necessary. In Fig. 9 the elements shown at the end of the pencil in Fig. 1 are provided for and numbered in the same way but the pencil part is omitted so that this is an eraser as an article of manufacture.

In introducing spare leads into the magazine 13 it is necessary to project the clip 23 to the outside and remove it from the screw head 21 because the bottom of this clip constitutes a cover for both magazines. In this position the magazines can be filled or a lead can be taken out for use.

The eraser can be operated by the fingers of one hand whereas it has been necessary heretofore in movable erasers to use the fingers of two hands for this purpose. This construction also provides an increased capacity for the eraser. Some features of the invention can be used in round or other forms.

Having thus described my invention and the advantages thereof, I do not wish to be limited to the details herein disclosed, otherwise than as set forth in the claims, but what I claim is:—

1. As an article of manufacture, an eraser casing having a cylindrical passage therein, a screw in said passage having a flat end, said passage

having means for receiving the flat end of the screw to prevent the screw from turning, the casing having an opening entirely through it registering with said passage, a nut in said opening fitting the threads of said screw, whereby the rotation of the nut will move the screw longitudinally in the casing, the screw having a head thereon, a metal clip for holding a rubber having a lateral slot for receiving said head, said casing having a recess open at the end in which the 10 clip and rubber can be received, whereby the rubber can be projected from the end of the casing for erasing purposes.

2. In an eraser combination with a thin flat casing having a thin rectangular compartment 15 opening at the end of the casing and a central compartment beyond the first named compartment, a screw in the central compartment, a nut on the screw, means on the casing for preventing the nut from moving longitudinally, means 20 for preventing the screw from turning, and readily detachable means on the screw for connecting it with an eraser in said first compartment.

3. The combination of a thin casing, a nut held thereby from longitudinal motion, a screw 25 passing through the nut and capable of being moved by the nut, said screw having a head on the end and a clip for holding an eraser in the casing, said clip having a slot open at one side for receiving said head so that the screw and 30 clip are detachably connected.

CARL C. HARRIS.
